William B. Sewell, Los Angeles, Calif., assignor to Sewell Products Inc., Los Angeles, Calif., a corporation of California

Application February 4, 1952, Serial No. 18,356

Term of patent 3½ years

(Cl. D34—15)

To all whom it may concern:

Be it known that I, William B. Sewell, a citizen of the United States, residing in the city of Los Angeles, county of Los Angeles, and State of California, have invented a new, original, and ornamental Design for a Toy Gun, of which the following is a specification, reference being had to the accompanying drawings, forming a part thereof.

Fig. 1 is a perspective view of a toy gun, showing my new design, taken from one side thereof; Fig. 2 is a rear view; Fig. 3 is a top plan view; and, Fig. 4 is a view taken of the other side thereof.

I claim:

The ornamental design for a toy gun, as shown.

WILLIAM B. SEWELL.
